UNITED STATES PATENT OFFICE.

CHARLES P. FUHRMANN, OF ERIE, PENNSYLVANIA, ASSIGNOR TO AMERICAN CAN COMPANY, OF NEW YORK, N. Y., A CORPORATION OF NEW JERSEY.

PIPE-BAND WIRE-LOOPING MACHINE.

1,072,844.

Specification of Letters Patent. Patented Sept. 9, 1913.

Application filed February 20, 1911. Serial No. 609,561.

To all whom it may concern:

Be it known that I, CHARLES P. FUHRMANN, a citizen of the United States, residing in Erie, in the county of Erie and State of Pennsylvania, have invented a new and useful Improvement in Pipe-Band Wire-Looping Machines, of which the following is a specification.

My invention relates to improvements in machines for making wire looped sheet metal bands, such as are used for securing coverings on steam and other pipes.

The object of my invention is to provide a wire looping pipe band machine of a simple, efficient and durable construction, by means of which wire loops may be rapidly and cheaply formed and automatically attached or applied to flat sheet metal pipe band strips.

My invention comprises in coöperative combination, a feeder for the wire from which the wire loops are to be cut, a stationary loop former horn under which the wire is fed and which receives the sheet metal band strip and supports it in position for attachment of the wire loop when formed, a gage and cutters for severing the wire into lengths, a movable loop forming die coöperating with the horn to partially bend and form the loop about the horn, movable folders for closing the ends of the partially formed wire loop about the horn and the band strip thereon, a band strip bender for turning the projecting end of the band strip about the folded ends of the wire loop, and a movable band strip closing or folding die for coöperating with the horn to close the turned end of the band strip about the wire loop and thus attach the same securely thereto.

My invention also consists in the novel construction of parts and devices and in the novel combinations of parts and devices herein shown and described and more particularly specified in the claims.

In the accompanying drawing forming a part of this specification, Figure 1 is a plan view of a sheet metal band strip wire looping machine embodying my invention. Fig. 2 is a vertical section on line 2—2 of Fig. 1. Fig. 3 is an enlarged detail, partial plan view. Fig. 4 is a detail, vertical section on the broken line 4—4 of Fig. 1. Fig. 5 is a similar sectional view showing the parts

in a different position with the wire folding dies closed to complete the folding or forming of the wire loop about the horn. Fig. 6 is a detail section on line 6—6 of Fig. 1. Fig. 7 is a detail, vertical section showing the band strip closing or folding die in its closed position. Fig. 8 is a detail, sectional view on line 8—8 of Fig. 1, showing the clutch, Fig. 9 is a detail section on line 9—9 of Fig. 1, showing the wire gripper or holding die, and Fig. 10 is a perspective view of a completed article as produced by my improved machine.

In the drawing, 1 represents the frame of the machine, which may be of any suitable form or construction, adapted to give support to the other parts, 2 the sheet metal band strip to which the wire loop 3 is to be attached, and 4 the wire from which the wire loop is cut and formed. The wire 4 passes from a suitable reel, not shown, through a set of horizontally arranged wire straightening rolls 5, and a similar set of vertically arranged wire straightening rolls 6 and suitable guides 7 under the loop forming and band strip supporting horn 8 on the stationary frame of the machine, the wire being advanced intermittently by the movable wire feeder 9 the requisite length to form a wire loop. The wire feeder 9 is preferably carried by a vibrating lever 10 and the wire is held stationary during the back stroke of the feeder by a movable gripper or wire holder 11, which coöperates with the stationary gripper or holder 12, and which is preferably operated by a lever 13. A stationary gage or stop 14 against which the front end of the wire abuts accurately regulates the length of wire to be cut for each wire loop 3. The wire loop is cut from the wire by a stationary cutter 15, coöperating with a movable cutter 16, preferably carried by or formed integral with the movable wire loop former die 17 which has a groove 18 to receive the severed piece of wire, and which coöperates with the band strip supporting and wire loop forming horn 8 to partially form the wire loop or bend the ends 19 of the severed piece of wire 20 upward into the position shown in Fig. 5 of the drawing, after which a pair of movable wire loop folders 21, 21, one on each side of the horn, move horizontally inward toward the horn and fold and close the

ends of the wire loop snugly down against the horn, the movable folders 21 having grooves 22 to receive the wire.

The movable wire folders 21 then withdraw and the band strip bender 23 then moves upward, as indicated in dotted lines in Fig. 7 and turns the projecting end 24 of the band strip upward into the position shown by dotted lines in Fig. 7. During this upward turning or bending of the projecting end of the band strip, the band strip is held snugly against the horn by the wire loop 3 which has previously been closed down against the band strip and thus operates to firmly clamp the band strip to the horn. After this operation of the band strip bender, the band strip folding or closing die 25 next moves horizontally and downwardly and against the upturned end 24 of the band strip and folds and closes it down and around the wire loop flat and snugly against the band strip, as will be readily understood from Fig. 7 of the drawing.

A stationary gage 26 on the frame of the machine and against which the extreme end of the band strip abuts, regulates the length of the projecting portion 24 of the band strip beyond the end of the horn 8, and thus the length of the fold formed in the band strip to hinge the wire loop 3 thereto. The table or support 27 upon which the sheet metal band strip rests may be formed integral with the horn 8. It is preferably provided with side gages or guides 28, which, in connection with the gage 26, enables the operator to readily and quickly place the band strip in proper position to receive the loop wire.

29 is the driving shaft, furnished with a pulley 30 and clutch 31 for connecting and disconnecting the driving pulley with the driving shaft.

Motion may be imparted from the driving shaft to the several movable parts or devices of my machine by any suitable connecting mechanism. The wire feeder lever 10 is, however, preferably operated by a cam 32 on the driving shaft. The wire gripping or holding lever 13 is preferably actuated by a cam 33 on the driving shaft. The movable wire loop former 17 and cutter 16 carried thereby are preferably operated by a vertically movable slide 34, mounted in suitable guides 35 on the frame of the machine and actuated by a cam 36 on the driving shaft through a connecting lever 37, which has an adjustable connection 38, 39 with the slide 34. The band strip bender 23 is preferably connected to and operated by the slide 34 by a further movement imparted to said slide by the high portion 40 of the cam 36.

The horizontally movable wire loop folders 21 are preferably operated by horizontally moving slides 41, moving in guides 42 on the frame of the machine and pro-

vided with racks 43 engaging gears 44 on the frame of the machine which are turned as required by racks 45 on the transverse slides 46, which are actuated by cams 47 on the driving shaft 29.

The band strip folding or closing die 25 is preferably carried by a vertically vibrating lever 48, mounted on a horizontally reciprocating slide 49, moving in suitable guides 50 on the frame of the machine. The required horizontal movement is imparted to this band strip folding and closing die 25 by a cam 51 on the driving shaft 29, which engages a roller 52 on said horizontally moving slide; and its required vertical or up and down movement is imparted to this folding or closing die 25 by a cam 53 on the driving shaft which engages said lever 48. A spring 54 is interposed between the lever 48 and slide 49 to move the lever 48 in the opposite direction.

I claim:

1. In a machine for forming and attaching wire loops to sheet metal pipe band-strips, the combination of a wire feeder, with a band-strip supporting and wire-loop forming horn, cutters for severing the wire, a movable wire-loop former coöperating with said horn, wire-loop folders to fold the end portions of the wire-loop around the horn, and clamp the band-strip against the horn, a movable band-strip bender to turn the projecting end of the band-strip at an angle, and a band-strip folding and closing die to fold and close the bent end of the band-strip flat against the band-strip and the portion of the wire loop embraced thereby, substantially as specified.

2. In a machine of the class described, in combination, a supporting and forming horn adapted to support a wire-band, means for feeding the wire to a position adjacent the horn, wire cutters, a wire-loop former coöperating with said horn, folders for completing the wire-loop, a band-strip bender, and a folder for completing the bend of the band strip.

3. In a machine of the class described, in combination: mechanism for bending a wire to form the same into a loop; movable folders adjacent said bending mechanism adapted to complete the formation of the wire loop and operating after said bending mechanism; a band-strip bender adjacent said bending mechanism and operating to bend the end of a band around a portion of the wire loop after the latter is formed; and a folder for completing the bend of the band-strip, substantially as specified.

4. In a machine of the class described, in combination, a wire-loop former, mechanism coöperating with said former for bending said wire to form a loop therein, folders coöperating with said former for completing the wire-loop, a band-strip

bender, a folder for completing the bend of the band-strip and operating after the bender, and wire cutters adapted to cut the wire into lengths, substantially as specified.

5 5. In a machine of the class described, in combination, wire feeding means, wire cutting means, a wire-loop forming device, movable folders coöperating with said device for completing the wire-loop after the 10 same has been partially formed, a band-strip bender operating to bend the end of a band around a portion of the wire loop and a folder operating after the bender for completing the bend of the band-strip, 15 substantially as specified.

6. In a machine of the class described, in combination, a forming and supporting horn, a wire feeder adapted to feed the wire to a position adjacent said horn, wire 20 cutters, wire-loop forming mechanism co-operating with said horn, wire-loop folders, a band-strip bender, and a band-strip folder.

7. In a machine of the class described, in combination, a forming and supporting horn, means for feeding a wire to a position adjacent said horn, a gage for the end of the wire to abut against, a wire-loop former coöperating with said horn, wire- 25

loop folders, a band-strip bender, and a 30 band-strip folder.

8. In a machine of the class described, in combination, a forming and supporting horn, a wire feeder adapted to feed the wire to a position adjacent the horn, wire cutting 35 means, a wire-loop former coöperating with said horn to form the wire into a loop, wire-loop folders to complete the formation of the loop, a band-strip bender, a band-strip 40 folder, and a gage for the end of the band strip to abut against, to properly position the same before the bending and folding operations take place.

9. In a machine of the class described, in combination, a supporting and forming 45 horn, means for forming a loop in a wire co-operating with said horn, wire-loop folders adapted to complete the formation of the loop, a band-strip bender coöperating with said horn, a band-strip folder adapted to 50 complete the bend in the band, a gage for the end of the band-strip to abut against, and a side guide for the band-strip.
